UNITED STATES PATENT OFFICE.

WILLIAM H. HUNTER, OF FARNHAMVILLE, IOWA.

CULTIVATOR.

SPECIFICATION forming part of Letters Patent No. 333,227, dated December 29, 1885.

Application filed October 6, 1883. Renewed June 16, 1884. Serial No. 135,045. (No model.)

To all whom it may concern:

Be it known that I, WILLIAM H. HUNTER, a citizen of the United States of America, residing at Farnhamville, in the county of Calhoun and State of Iowa, have invented certain new and useful Improvements in Cultivators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain improvements in cultivators; and it consists of the improved construction, fully described herein-after, whereby the height of the draft-frame and tongue can be readily adjusted with respect to the beams and shovels, the beams readily attached to the frame at different vertical and lateral adjustments, and the general construction improved and simplified.

20 In the accompanying drawings, Figure 1 is a side view of a cultivator constructed in accordance with my invention. Fig. 2 is a front view of the same. Fig. 3 is a perspective view of one of the beam-sections. Fig. 4 is a detail view of one of the shovels and part of 25 a standard. Fig. 5 is a detail view, and Fig. 6 another detail view.

A represent two vertical standards formed at their lower ends into square frames *a b*, provided with an elongated opening, *c*, in the top bar, and a series of perforations, *c'*, in the bottom bar of the same, and stub-axes *C*, formed integrally with the side bars of said frame, upon the ends of which axles turn the carrying-wheels *D*. An arched bar, *E*, spans the 30 two vertical standards *A B*, and is provided at its vertical ends with loops *d d*, which embrace the said standards, connecting the arched bar to said standards, but permitting a vertical adjustment of the former on the latter. Centrally on the top of the arched bar is secured, by bolts or otherwise, the rear end of the draft-tongue *F*, which is braced by rigid diagonal and horizontal braces *e e*, secured to said tongue, and extending back for a distance in 35 the rear of the arched bar, and secured thereto where they cross the same.

Inclined rods *f*, bolted at their lower ends

to the lower inner sides of the standards *A B*, extend nearly to the draft-tongue *F*, and rods *f'* of a corresponding length, bolted at their upper ends to the said draft-tongue, extend nearly to the lower end of the rods *f*, and are retained in connection therewith by a loop, *f''*, two rods, and loop connections forming vertically-extensible braces for the tongue. A 55 double-tree, *G*, is pivotally secured to the tongue, and a pivoted neck-yoke, secured to a swivel-pivot, is located at the front end of the tongue.

Both the vertical portions of the arched bar 60 and the standards *A B* are provided with a series of perforations, *h*, through which a securing-bolt, *h'*, is adapted to be passed to hold securely the arched bar in any of the vertical positions it may be adjusted upon the standards *A B*. The rods *f f'* have also perforations *i* and a bolt, *i'*, for effecting the secure adjustment of the rod *f'* on the rod *f*.

Within each frame *a b* is a vertical bar, *H*, provided with a series of perforations, *j*, and rounded at its lower end to bear in one of the perforations in the lower bar of each frame. Each of the said bars *H* is provided with a rib, *k*, which, in addition to the main portion *k'* of the body of the bar, can be readily passed 70 into each frame through the elongated opening in the top thereof, and the bar then turned to bring the rib beneath the bar adjacent to the elongated slot, to prevent the removal of said bar from the frame without turning the same, 75 the lower rounded end of the bar bearing in one of the perforations *c'* in the lower bar of the frame.

Links *I*, each having a head, *l*, at one end, are recessed at the other end to embrace the 80 bars *H*, and each has transverse perforations *m*, adapted to register with those in the bar, and be retained in connection with the said bar by means of a bolt passing through the perforations of said link and bar. The head 85 of the link *I* is bolted by a swivel-bolt between corresponding heads, *J J'*, of horizontal clamp-plates *K K'*. The upper clamp-plate, *K*, has a **U**-shaped groove, *n*, on its under side, and the lower plate, *K'*, has a corresponding groove, *n'*, which, when the plates are clamped rigidly together, form a **U**-shaped recess of sufficient size to receive the **U**-shaped 90 end of a double beam, *L L'*, which is placed

therein and the plates bolted together. The rear ends of the beam L L' are curved to form vertically-inclined standards M M', each having a shovel, p, formed with a straight upper edge, p', against which a supplemental shovel, p'', curved as shown in Fig. 4, can be bolted to act in the capacity of a mold-board for the lower shovel. A wedge-shaped block, q, interposed between the lower end of the standard and the rear faces of the shovel-sections p p'', increases the inclination of the shovel-sections, if desired.

Each beam-section has securely bolted between its rear horizontal parts a brace, r, having lugs r' r'', between which and the sides of the beams L L' the ends of the handles N can be inserted, a bolt passing through the beams, handle, and shoulders rigidly securing the several parts together.

20 If desired, an additional standard, O, as shown in Fig. 2, and its shovel t can be added to either the beam L or L'. The said standard O is horizontal at its upper end, t', and is laterally curved at said end, that its shovel 25 may be equidistant with respect to the shovels of the beams L L', and is beveled at the side of the said upper end to rest in a groove of a bearing-block, P, a bolt, r', passing transversely through the end t' of the standard, the bearing-block, and beam to securely fasten all the 30 parts together. A shouldered brace, u, designed to fill the office of the brace r, may be bolted between the standard O and the beam.

Clips Q embrace the vertical sides of the 35 arched bar and the standards A B, and are clamped thereto by clamp-plates having perforations through which the threaded ends v of the clips pass and retained by nuts w. The neck R of each clip is perforated to receive the end of a horizontal bar, s', which extends back over the beam-sections, and is provided with a chain, x, for attachment to the beam-sections, to more firmly brace the same with respect to each other and the draft-frame.

45 Hooked links T are hung in perforated ears

on the axle, and can be hooked to suitable chains or straps connecting with the collars of the team, so as to also secure a draft on a line with the axles.

By the construction of the cultivator described the draft-frame can be easily lowered or elevated with respect to the beams, and by moving the lower ends of the bars H, so as to rest in the different perforations c' of the frames, the beams, and their connections with the bars H, can be readily adjusted to any desired degree of lateral inclination, and that the parts composing the machine are of a construction tending to make the machine as a unit thereof both durable and simple, and that the said parts can be readily and conveniently cast with but little labor.

I claim—

1. In a sulky plow or cultivator, the frames having rigidly attached thereto stub-axles C 65 on one side and vertical standards on the other, in combination with an arched bar provided near its ends with loops, said bar supporting the tongue, and extensible and adjustable braces, the parts being organized substantially as shown, for the purpose set forth.

2. In a sulky plow or cultivator, the combination of an adjustable arched bar and carrying-frames with axles formed thereon, and provided with vertical standards and draft-bars for the plows or cultivators, the parts being organized so as to be vertically adjusted with respect to each other and braced by means of extensible and flexible stays, substantially as shown, and for the purpose set forth. 80

3. The combination, in a cultivator, of clips clamped to the draft-frame and carrying arms provided with crossed chains for bracing the beam-sections, substantially as set forth.

In testimony whereof I affix my signature in 85 presence of two witnesses.

WILLIAM H. HUNTER.
